DESIGN FOR A SHELF

Carl A. Goddard, Winchester, Mass., assignor to
Scully Signal Company, East Cambridge, Mass.,
a corporation of Massachusetts

Application April 17, 1946, Serial No. 128,669

Term of patent 14 years

(Cl. D33—3)

To all whom it may concern:

Be it known that Carl A. Goddard, a citizen of the United States, residing at Winchester, in the county of Middlesex and Commonwealth of Massachusetts, has invented a new, original, and ornamental Design for a Shelf, of which the following is a specification, reference being had to the accompanying drawing, forming part thereof.

The figure of the drawing is a perspective view of a shelf, showing my new design.

I claim:

The ornamental design for a shelf, as shown.

CARL A. GODDARD.
